UNITED STATES PATENT OFFICE

WILSON E. PORTER, OF NEW HAVEN, CONNECTICUT, ASSIGNOR TO THE NEW HAVEN CLOCK COMPANY, OF NEW HAVEN, CONNECTICUT, A CORPORATION

AUTOMATIC TIMING DEVICE

Application filed March 27, 1930. Serial No. 439,314.

This invention relates to an improvement in timing devices designed for automatically effecting a given operation, such as the opening or closing of an electric circuit, after the 5 lapse of a predetermined time-period.

The main object of this invention is to provide, at a low cost for manufacture, a simple, reliable and smooth-acting automatic timing device which may be readily reset to shorten 10 or terminate a previously-selected time-interval, without occasioning such wear as would materially affect the operation of the device over a long period of service.

A further object of this invention is to provide an automatic timing device of the character referred to which will provide against the overwinding of the driving-spring as the result of repeated setting and resetting.

With the above and other objects in view as 20 will appear from the following, my invention consists in an automatic timing device characterized by a driving-spring for the time-train having one end frictionally anchored in place; and a manually-operable member 25 frictionally connected to the frictionally-anchored driving-spring for tensioning the same; whereby the timing device may be set and reset without overwinding the said spring.

30 My invention further consists in an automatic timing device characterized as above and having certain details of construction and combinations of parts as will be hereinafter described and particularly recited in the 35 claim.

In the accompanying drawings:

Fig. 1 is a view in front elevation of one form which an automatic timing device constructed in accordance with my invention may 40 assume;

Fig. 2 is an edge view thereof upon a larger scale;

Fig. 3 is a transverse sectional view taken on the line 2—2 of Fig. 1 but on a larger scale;

45 Fig. 4 is a sectional view taken on the line 4—4 of Fig. 2;

Fig. 5 is a similar view taken on the line 5—5 of Fig. 2;

50 Fig. 6 is a corresponding view taken on the line 6—6 of Fig. 2;

Fig. 7 is a detached perspective view of the cocking-disk;

Fig. 8 is a similar view of the control-disk; and

55 Fig. 9 is a broken transverse sectional view illustrating another mode of frictionally anchoring the outer end of the main-spring to prevent the over-winding thereof.

60 In the embodiment of my invention herein chosen for illustration in Figs. 1 to 8 inclusive, I employ a winding-arbor or shaft 10 mounted for rotation in a rear assembly-plate 11 and an intermediate assembly-plate 12 and extending forward through a front assembly-plate 13 and a dial-plate 14. The 65 plates 11 and 12 are held in spaced relationship by means of pillars 15 and, similarly, the plates 12 and 13 are held in spaced relationship by pillars 16.

70 Near its rear end the winding-arbor or shaft 10 is provided with a hook or pin 17 with which the inner end of a spiral driving-spring 18 is engaged in the usual manner of clock main-springs, while the outer end of the said spring frictionally engages the 75 interior surface of the flange of a cup-shaped spring-barrel 19 concentrically positioned with respect to the arbor or shaft 10 and secured to the forward face of the rear plate 11 by means of rivets 20. To heighten the 80 frictional engagement between the outer coil of the spiral spring 18 and the inner face of the flange of the spring-barrel 19, I secure thereto a short reinforcing-strip 21 of 85 spring-stock by means of a rivet 22, as clearly shown in Fig. 6 of the drawings.

Staked to the winding-arbor or shaft 10 just forward of the spiral spring 18 is a ratchet-wheel 23, upon the hub 24 of which is mounted, with freedom for rotation, a 90 main-wheel 25 held in place by means of a retaining-washer 26 and carrying upon its forward face a pawl 27 engaging with the teeth of the ratchet-wheel 23 under the urge of a spring 28.

95 The main-wheel 25 meshes into and drives a first pinion 29 mounted upon an arbor 30 carrying a second wheel 31 meshing into and driving a second pinion 32 mounted upon an arbor 33 carrying a third wheel 34. The 100

third wheel 34 meshes into and drives a pinion 35 upon an arbor 36 which carries the fourth wheel 37 which, in turn, meshes into and drives a pinion 38 mounted upon the arbor 39 of an escapement-wheel 40 coacting in the usual manner of time-trains with an escapement-lever 41 which imparts oscillatory movement to a balance-wheel 42.

The wheels, pinions, etc., 25 to 42 inclusive, 10 are positioned between the rear plate 11 and the intermediate plate 12, as clearly shown in Fig. 2 of the drawings.

The forward end of the winding-arbor or shaft 10 is reduced in diameter to form a 15 stem 43 upon which is mounted, with freedom for rotation, a setting-sleeve 44 having its inner end facing a forwardly-facing shoulder 45 formed at the junction of the stem 43 and the intermediate portion 46 of 20 the winding-arbor or shaft 10. The said sleeve is retained in place against outward axial displacement upon the stem 43 of the arbor or shaft 10 by means of a bifurcated key 47 clipped into an annular groove 48 25 near the extreme forward end of the said stem.

Positioned upon the outer end of the sleeve 44 is a finger-button 49 provided with an inwardly-opening axial bore 50 for the reception of the outer end of the said sleeve, to which it is coupled by means of a coupling-screw 51. The inner end of the finger-button 49 mounts a pointer 52 adapted to sweep over an annular series of graduations 53 engraved or etched upon the forward face of the dial-plate 14 before referred to.

The inner face of the sleeve 44 has placed against it a hardened friction-washer 54 engaged by a split spring-washer 55 engaging 40 at its rear end with a hardened friction-washer 56 resting against a washer 57 staked upon the winding-arbor or shaft 10 against the shoulder 45 thereon.

For the purpose of controlling an electric switch or any other device which it may be desired to control, I employ a cocking-disk 58 staked upon the sleeve 44 near the rear end thereof and formed in its periphery with a notch 59, one wall of which is tangentially sloped, as shown in Fig. 7, to form a cam-surface 60 for coaction with a shoe 61 offsetting from the free end of a flexible switch-arm 62.

The opposite end of the switch-arm 62, 55 as shown, is mounted upon a block 63 of insulating material forwardly offsetting from the intermediate plate 12 to which it is secured by means of screws 64. The flexible switch-arm 62 also carries a contact 65 engageable with a similar contact 66 upon a complementary flexible switch-arm 67 when the shoe 61 is moved outwardly upon the periphery of the cocking-disk 58 as will hereinafter appear.

65 The inner end of the sleeve 44 is also

formed with a bearing-surface 68 located immediately to the rear of the cocking-disk 58 and upon which is mounted, with freedom for limited rotation, what I shall for convenience of description refer to as a "control-disk" 70 69 which is formed with a notch 70 resulting in the formation of a drop-off nose 71 which, as will hereinafter appear, is adapted to overlap the cam-surface 60 of the adjacent cocking-disk 58.

As before pointed out, the cocking-disk 58 is rigidly coupled to the sleeve 44 while the control-disk 69 may turn upon the bearing 68 of the said sleeve. Now, for the purpose of coupling the control-disk 69 to the cocking-disk 58 for movement therewith, but with capacity for limited relative movement, I provide the said cocking-disk with a rearwardly-projecting pin 72 extending through an arcuate slot 73 in the control-disk 69 and having one end of a helical spring 74 hooked over its rear end. The opposite end of the said spring is hooked over the rear end of a pin 75 rearwardly projecting from the control-disk 69. 80 85

The spring 74, just above described, exerts a constant effort to turn the control-disk 69 with respect to the cocking-disk 58 in a direction required to cause the drop-off nose 71 of the former to overlap the cam-surface 60 of the latter. 90

In the operation of my improved timer, the user grasps the finger-button 49 and turns the same clockwise until the pointer 52 carried thereby registers with the graduation upon the dial 14 indicating the particular time-interval which it is desired to have elapse before the automatic accomplishment of a function such as the opening of a circuit, as is herein illustrated. 100 105

For the purpose of description, let it be supposed that the desired interval is fifteen minutes.

As the finger-button 49 is turned clockwise, as above described, to register the pointer 52 with the desired graduation, the winding-sleeve 44 is turned and through the intermediary of the split spring-washer 55 and associated parts, effects the turning of the winding-arbor or shaft 10 and the winding 110 115 of the driving-spring 18.

It will thus be seen that, although the sleeve 44 with its button 49 and associated disks 58 and 69 constitutes the setting means for the device, it will, through the frictional coupling described, operate to wind the spring 120 125 18.

Concurrently with the turning of the finger-button 49 and the pointer 52, the cocking-disk 58 will also be turned so as to cause the cam-surface 60 thereof to move the shoe 61 of the switch-arm 62 outward and flex the latter so as to engage its contact 65 with the contact 66 of the switch-arm 67 and thus 130 close the circuit. 125

As the cocking-disk 58 is turned, as just above described, to move the shoe 61, the control-disk 69 will remain stationary until the shoe has been moved to a sufficient degree to permit the drop-off nose 71 thereof to be snapped under it by the spring 74, this being effected by virtue of the fact that the cocking-disk is of slightly greater diameter than the control-disk.

10 The continued rotation of the parts propelled by the finger-button 49 until the pointer 52 registers with the fifteen-minute graduation upon the dial-plate 14, will bring the parts into the positions in which they are 15 shown in the drawings, in which the shoe 61 is resting upon the periphery of the cocking-disk 58.

Upon the setting of the device as just above described and the removal of any manual restraint upon the finger-button 49, the driving-spring 18 will immediately assert itself and slowly turn the arbor or shaft 10 counter-clockwise under the control of the time-train already described. This counter-clockwise 25 rotation of the arbor will also effect the similar rotation of the disks 58 and 69 and the pointer 52 for the reason that the sleeve 44 is frictionally coupled to the said arbor by the split spring-washer 55 and its associated parts.

When the pointer 52 has reached the zero mark upon the dial-plate 14, the drop-off nose 71 of the control-disk 69 will have ridden out from under the shoe 61 which will immediately snap inward under the tension of the resilient switch-arm 62 with the result that the contact 65 will be separated from the contact 66 and the circuit thus broken, all as more completely shown and described in 40 my co-pending application of the same title filed March 14, 1930, Serial No. 435,792, now Patent No. 1,831,605, dated Nov. 10, 1931.

Let it be supposed that the user wishes to shorten or terminate a previously-selected 45 time-interval for which he has set the timer. This may readily be accomplished by turning the finger-button 49 counter-clockwise which will effect a similar turning movement of the pointer 54, sleeve 44 and disks 58 and 69. 50 During this resetting operation, the friction coupling action of the split spring-washer 55 will yield, since the winding-arbor or shaft 10 is held against any counter-clockwise movement by the ratchet-wheel 23, pawl 27, 55 main-wheel 25 and the remainder of the time-train. Thus, the driving-spring 18 is still maintained under tension.

It will be readily seen that, were not provision made for its prevention, the repeated 60 setting and resetting of the timing device would ultimately wind the driving-spring 18 to such a degree as to prevent the further clockwise rotation of the finger-button

51 without breaking the said spring or some of the connecting parts.

In my improved device it will be noted that the outer end of the spiral driving-spring 18, instead of being fixedly anchored, as is its end which is connected to the arbor or shaft 10, is frictionally anchored by the frictional grip of its outer convolution assisted by the reinforcing-strip 21, upon the inner surface of the flange of the spring-barrel 19 so that when the said spring is wound to a predetermined degree, it will automatically overcome the frictional grip of its outer convolution upon the said spring-barrel and cause a relative slippage and thus automatically relieve the said spring of any excess tension.

Instead of effecting the frictional anchorage of the outer end of the spiral driving-spring by means of the frictional engagement thereof with the spring-barrel 19, I may effect a similar result by anchoring the outer convolution of the said spring to the spring-barrel by means of a rivet 76 (Fig. 9) and frictionally anchoring the spring-barrel itself to the rear plate 11 by providing it with a rearwardly-extending bushing 77 bearing in the said plate 11 and provided at its rear end with a spring-washer 78 bearing against the rear face of the said plate and exerting a constant effort to engage the rear face of the spring-barrel with the front face of the said plate, as shown in Fig. 9 of the drawings.

It will be understood by those skilled in the art that my invention may assume varied physical forms without departing from my inventive concept and I, therefore, do not limit myself to the specific embodiment herein chosen for illustration, but only as indicated in the appended claim.

I claim:

In an automatic timing device, the combination with the time-train and control-mechanism therefor, of manually-operable winding means, and manually-operable setting means, said winding means including a shaft, a driving-spring for said time-train having one end frictionally anchored to a portion of the timer-structure and its other end fixedly connected with said shaft, said setting means including a sleeve carried by said shaft and rotatable relatively thereto and provided with means whereby it may be manually rotated, means including a member rigid on said shaft and a spring member bearing thereagainst and against said sleeve to provide a frictional coupling between said sleeve and shaft whereby rotation of said sleeve in one direction will rotate said shaft to wind said spring, and means for preventing unwinding of said spring by reverse rotation of said sleeve.

WILSON E. PORTER.
